DOOR OPERATING MEANS

Charles Cakora, Lyons, Ill., assignor to G. S. Blakeslee & Co., Cicero, Ill., a corporation of Illinois

Application April 11, 1932, Serial No. 604,423

7 Claims. (Cl. 268—16)

This invention relates to door operating means, and is more particularly directed to a door operating mechanism for raising and lowering a plurality of sliding doors simultaneously.

5 In the preferred embodiment of the invention I have disclosed the door operating means in conjunction with a pair of sliding doors on a dish washing machine, but it is to be understood that the invention is equally applicable to a variety of other structures.

The door operating mechanism preferably comprises eccentrically mounted pulleys or sheaves, mounted upon a common shaft, which shaft is maintained under the tension of a spring by 15 means of a ratchet and pawl locking connection. Connected to the pulleys are suitable door operating cables, which are secured to the doors and which are wound and unwound upon the pulleys for raising and lowering the doors.

20 The eccentrically mounted pulleys are so disposed that when the doors are in lowered position, the weight of the door and the length of the effective lever arm of the pulley are such as to prevent raising of the door by the spring. 25 However, when the doors are in raised position, the pulley has been rotated to an extent such that the weight of the door and the length of the effective lever arm of the pulley are insufficient to overcome the tension of the spring and 30 lower the door. Thus the doors are maintained in either open or closed position automatically, and no latching means for positioning the doors in either of these positions is required.

The operating mechanism is constructed as 35 an enclosed unit, and may be positioned to operate parallelly spaced doors, or may be angled in position to operate doors extending normal to each other, without any modification of the door operating structure itself.

40 The invention, in its broader aspects, is also applicable to the operation of a single door, or a plurality of doors, as desired.

Other objects and advantages of the present invention will appear more fully from the following detailed description, which, taken in connection with the accompanying drawings, will disclose to those skilled in the art the particular construction and operation of a preferred embodiment of my invention.

45 50 In the drawings:

Figure 1 is a side elevational view of a dish washing machine provided with the door operating means;

Figure 2 is a front elevational view of the dish 55 washing machine disclosed in Figure 1;

Figure 3 is a plan view of the dish washing machine, provided with door operating structure as shown in Figure 1;

Figure 4 is a modified form of dish washing machine, in which the doors are positioned normal to each other, provided with the door operating unit; 60

Figure 5 is a sectional view through the door operating unit, showing the details of construction of the pulley and the associated shaft and 65 spring tension means;

Figure 6 is a detail sectional view taken on the line 6—6 of Figure 5, with the door lowered;

Figure 7 is a view similar to Figure 6, showing 70 the position of the pulley when the door is raised; and

Figure 8 is a sectional view taken substantially on the line 8—8 of Figure 5, showing the details of the locking mechanism for the spring tension adjustment. 75

Referring now to the drawings in more detail, in Figures 1 to 3, inclusive, I have shown a dish washing machine of known type, a base 1, a casing 2, and suitable legs 3. The legs 3 are interconnected by cross bracing members 4, which support the motor, pump and other apparatus connected to the washing and spraying members within the casing, and to a tank in the lower portion of the casing. The casing 2 is provided with a pair of oppositely disposed doors 5, provided adjacent their lower edges with handles 6, and sliding in suitable guides 7 carried by the casing 2. 80

Suitably supported tables 9 and 10 extend from casing 2 and are disposed to receive and support 90 the trays of dishes as they are slid into and out of the casing.

Disposed upon the top of the casing 2, and extending from front to back thereof, is a housing 11 which contains the door operating mechanism. The mechanism comprises a pair of spaced coaxial pulleys enclosed in pulley housings 12 and 13. Connecting the pulley housings 12 and 13 is a substantially inverted U-shaped housing member 14, which is disposed over a connecting shaft between the two pulleys. 95

In Figure 4 I have shown a modified type of washing machine, in which the tables 9' and 10' are mounted at right angles to each other, and the door members 5' are therefore normal to each other. In this modification, the door operating mechanism 11 is mounted diagonally across the top of the casing 2, but is identical in construction with the door operating mechanism shown in Figures 3 and 5. 100

- Referring now in detail to Figures 5 to 8, which are sectional views showing the construction of the door operating mechanism, the housing or unit 11 is preferably mounted upon the top wall 15 of the casing 2, and extends the entire distance between the side walls 16 of the chamber. The pulley housings 12 and 13 are preferably cup-shaped, and each is provided with an inwardly extending bearing sleeve 18, which sleeves rotatably support a shaft 19 extending between the two housings. Suitable cover plates 20 are secured to the outer side of each of the housings 12 and 13, as by means of the screws 21 and 22, and serve therewith to enclose the pulleys.
- As shown in Figures 6 and 7, a pulley sheave 23 is disposed within each of the pulley housings and is suitably keyed to the shaft 19, by means of a key member 24. The sheave 23 is provided with a shoulder 25, which bears against the inner surface of the housing 12.
- Each of the sheaves 23 is provided with a cable 26, one end of which is secured to the sheave by means of a screw 27, which threads into the sheave.
- The cable 26 extends down through a suitable channel 28 formed in the respective housings 12 and 13, and through an opening 29 formed in the top wall 15 of the casing 2, and is suitably secured at its lower end to an angle bracket 30 secured to the sliding door 5 adjacent the lower edge thereof. It will be noted, from Figure 2, that the cable is secured off center with respect to the door, which produces a binding action upon the door when it is in raised position, and thus serves to hold the door in such position. It will be noted that the door guides extend only a slight distance above the door when the door is in lowered position. Upon raising of the door to its upper position, a major portion of the door projects above the guides. This provides for cocking or binding of the door with respect to the guides, due to the pull of the cable applied on one side of the center of the door. This pull tends to cock the door and bind it against downward movement. When the door is lowered, the pull of the cable is released, allowing the door to drop back into proper cooperation with the guides, and as the door is lowered no further binding occurs since the guides prevent lateral tilting of the door. This action is produced whether the door be manually raised and lowered, or whether it be raised and lowered automatically by manual operation of the other door. A bushing 32 is secured on shaft 19, between the housings 12 and 13, by means of a taper pin 33. A spacing member 34 is positioned about the shaft 19 between the bushing 32 and a second bushing 35 which is suitably recessed to receive bearing member 18 of the pulley housing 12.
- Member 18 of the pulley housing 12 is provided with a ratchet 36, as shown more clearly in Figure 8. A suitable tension spring 38 is coiled about the spacing member 34 and has an end thereof secured in the opening 39 of flange 32a of bushing 32. At its other end, the spring 38 is non-rotatively secured, by means of the angularly bent portion 40, to flange 35a of the bushing 35, thus positioning the spring 38 between the two bushings 32 and 35 to serve as a tension means therebetween. The radially flanged portion of the bushing 35 also carries a suitable pin 42, which serves as a pivot for a pawl 43, which engages the teeth of ratchet 36 of the pulley housing 12.
- Through the ratchet and pawl means, the bush-

ing 35 can be adjusted to place the spring 38 under any desired tension. This tension is transmitted through the bushing 32 and the taper pin 33 to the shaft 19, and tends to rotate the pulleys 23 in door raising direction.

Referring now in more detail to the pulleys 23, it will be noted, in Figures 6 and 7, that the pulleys are eccentrically mounted with respect to the shaft 19. The pulleys are so disposed that, when the door is lowered each pulley occupies the position shown in Figure 6, in which the effective length of the lever arm of the pulley for raising the door is the distance indicated by X, and when the door is raised the pulley occupies the position shown in Figure 7, in which the effective length of the lever arm for holding the door raised is indicated by Y.

The pulley 23 is shown in Figure 6 as being in the position corresponding to the lowermost position of the door 5, and the weight of the door, acting through the lever arm of the length X overcomes the tension of spring 38 tending to open the door, so that the door remains in its lowered position. The spring 38 assists in raising the doors. In the fully raised position of the doors the moment of the weight of the door times the length Y of the effective lever arm of the pulley is less than the turning moment imparted to shaft 19 by the spring 38, and the doors remain in their uppermost position. As will be apparent from Figures 6 and 7, this produces an inverse variation between the effective length of the lever arm and the effective arm of the rotating means. Thus, while in Figure 6 the pulley lever arm length is indicated by the dimension X when the door is in lowered position, in Figure 7 this length has decreased to a length indicated by the dimension Y, when the door is in raised position. Correspondingly, the effective moment of the rotating means increases as the door is raised.

When the doors are moved downwardly the pulleys are again rotated, and, when the doors reach their lowermost position, the moment of the tension spring 38 is not great enough to counteract the moment of the weight of the door times the effective length X of the lever arm, and the doors remain in lowered position.

The doors are operated simultaneously and similarly, and the eccentric mounting of the pulleys 23 serves to retain the doors either in their lowered position or in their raised position, without the use of any latching means. By rotating the bushing 35 the tension of member 38 can be adjusted with facility to suit conditions. The size of the pulley may be varied, but should be such that in the lowered position of the doors the maximum length of pulley arm is effective, and in the raised position of the doors, the minimum length of pulley arm is effective. The pulley may rotate through a half revolution, or one and a half revolutions, or any other suitable distance during movement of the doors from lowered to raised position, or vice versa, to produce this result.

The tension spring may extend substantially the entire length of the shaft connecting the two pulleys, if desired, but ordinarily sufficient tension can be provided by a spring member extending only partially the length of the shaft between the pulleys. The entire operating mechanism is fully enclosed and is of simple and compact construction, and requires no special assembling knowledge or skilled operation. As shown in Figures 3 and 4, the operating mechanism can

- be disposed for parallelly spaced sliding doors, normally positioned sliding doors, or other positional arrangement of the doors, without any change of construction.
- 5 I do not intend to be limited to the exact details shown and described in connection with the preferred embodiment of the invention illustrated, but only in so far as defined by the scope and spirit of the appended claims.
- 10 I claim:
1. In combination, a shaft, pulleys eccentrically mounted thereon at each end of said shaft, door guides, a plurality of doors in said guides adapted to be raised and lowered by rotation of said pulleys and connected to said pulleys, the connection between said pulleys and said doors binding said doors against said guides when said doors are in raised position, means carried by said shaft and disposed between said pulleys tending to rotate said shaft in a raising direction, and means for varying the tension in said last named means, the eccentricity of said pulleys increasing the effect of said rotating means when the doors are in raised position.
  2. In combination, a door, guides for said door, a shaft mounted above said door, a pulley eccentrically mounted on said shaft, an off-center connection between said pulley and said door adapted to bind said door when in raised position, a pulley housing forming a bearing support for said shaft, tension means for rotating said shaft, and means carried by said tension means and engaging said pulley housing for varying the tension of said tension means in accordance with the weight of the door to be raised.
  3. In combination, door guides, a door adapted to be raised and lowered in said guides, a rotatable shaft positioned above said door, a pulley eccentrically mounted on said shaft, means normally tending to rotate said shaft in raising direction, and an off-center connection between said door and said pulley, the eccentricity of said pulley causing the effective length of the pulley lever arm to vary inversely with respect to the effective arm of the rotating means during movement of said door, and said connection binding said door in raised position.

- 55
- 60
- 65
- 70
- 75
4. In combination, door guides, a pair of parallel spaced doors adapted for vertical sliding movement in said guides, a shaft disposed above said doors and extending therebetween, said shaft having eccentrically mounted pulleys disposed upon the ends thereof, tension means for normally rotating said shaft in one direction, and means connected between said doors and said pulleys for raising and lowering said doors, said means being adapted to bind said doors in raised position.
5. In combination, door guides, a pair of normally extending doors adapted for vertical sliding movement in said guides, a shaft disposed above said doors and extending angularly therebetween, said shaft having eccentrically mounted pulleys disposed upon opposite ends thereof substantially centrally of each of said doors, tension means for rotating said shaft, and connections between said doors and said pulleys, said connections being disposed on one side of said doors to bind said doors in raised position.
6. In combination, a structure having a pair of doors mounted for vertical sliding movement within corresponding door guides secured thereto, cables connected to said doors, a rotatable shaft on the top of said structure having a pair of pulleys for receiving said cables, said pulleys being mounted eccentrically on said shaft, and means tending to rotate said shaft in door opening direction, the moment of the doors and the effective length of the pulley arm decreasing as the doors are raised.
7. In combination, a vertically sliding door, door guides extending beyond the upper edge of said door when said door is in lowered position, a cable connected to said door at one side of the center thereof, a pulley eccentrically mounted above said door guides and receiving said cable, and tension means for rotating said pulley, said cable being tensioned and acting to cock said door with respect to said guides when said door is in raised position with the major portion thereof extending above said guides.
